MIXER FOR CULINARY AND GENERAL USE

Harold Eric Chapman, Ashford Bowdler, near Ludlow, England

Application June 17, 1950, Serial No. 10,612
In Great Britain December 16, 1949

Term of patent 14 years

(Cl. D44—8)

To all whom it may concern:

Be it known that I, Harold Eric Chapman, a British subject, residing at The Grove Farm, Ashford Bowdler, near Ludlow, in the county of Shropshire, England, formerly of 23 Glencoe Road, Sheffield 2, in the county of Yorkshire, England, have invented a new, original, and ornamental Design for a Mixer for Culinary and General Use, of which the following is a specification, reference being had to the accompanying drawing, forming part thereof.

I claim:

The ornamental design for a mixer for culinary and general use, as shown.

HAROLD ERIC CHAPMAN.
